UNITED STATES PATENT OFFICE.

FRED W. BOCKSTEGE, OF EVANSVILLE, INDIANA.

DESIGN FOR A COMBINATION BUFFET, CHINA CLOSET, AND DESK.

Application filed February 6, 1923. Serial No. 5,091. Term of patent 3½ years.

To all whom it may concern:

Be it known that I, FRED W. BOCKSTEGE, a citizen of the United States, residing at Evansville, in the county of Vanderburgh and State of Indiana, have invented a new, original, and ornamental Design for Combination Buffet, China Closet, and Desk, of which the following is a specification, reference being had to the accompanying drawing, forming a part thereof, which is a perspective view of a combination buffet, china closet, and desk, showing my new design.

I claim:

The ornamental design for a combination buffet, china closet, and desk, as shown.

In testimony whereof I affix my signature.

FRED W. BOCKSTEGE.
